(57) **CLAIM**

The ornamental design for a concrete and steel bench, as shown and described.

DESCRIPTION

FIG. 1 is a perspective view showing my new design of a concrete and steel bench;

FIG. 2 is a top plan view thereof;

FIG. 3 is a front elevational view thereof;

FIG. 4 is a bottom plan view thereof;

FIG. 5 is a rear elevational view thereof; and,

FIG. 6 is a left side elevational view thereof, which is the mirror image of the right side of the concrete and steel bench.

The broken lines shown on the backrest are for illustrative purposes only and form no part of the claimed design.
